LEWIS O. SCHULTZ, OF MATTOON, ILLINOIS.

Letters Patent No. 70,625, dated November 5, 1867.

IMPROVED CAR-COUPING.

The Schedule referred to in these Letters Patent and making part of the same.

TO ALL WHOM IT MAY CONCERN:

Be it known that I, LEWIS O. SCHULTZ, of Mattoon, Coles county, Illinois, have invented a new and useful Improvement in Car-Coupling; and I do hereby declare that the following is a full, clear, and exact description thereof, which will enable others skilled in the art to make and use the same, reference being had to the accompanying drawing, forming part of this specification.

The object of this invention is to provide a safe, cheap, and effective coupling for railroad cars, one that shall be composed of but few parts, and which shall couple the cars automatically; and the invention consists in attaching to the draw-head of the car a coupling-pin, and a guide-piece, and a hinged catch, all of which are made to operate effectively without the aid of springs or weights attached, as will be hereinafter fully described.

The drawing represents a longitudinal vertical section of my coupling, showing the different parts, and their proper location.

A represents the draw-head. B is the coupling-link. C is the coupling-pin. D is the guide for the link after the link passes into the draw-head, and which keeps the link in place. E is a guide-piece in the front part of the draw-head, which is adjustable, and which guides the link as it enters the draw-head, and which can be adjusted for cars of different heights. F is a hinged or pivoted catch on the upper part of the draw-head. The coupling-pin has a slot in it which allows it to slide up and down, and to work on a pin attached to the draw-head, seen at a. The pivot of the catch F is seen at e. F is raised by the rod d when the cars are to be uncoupled. In that case the hook f of the catch leaves the pin a, and the point of the catch g strikes the draw-head, thus giving the catch a lever purchase upon the pin. When the cars are to be coupled, as represented in the drawing, the link strikes the guide-pin E, over which it slides, and entering the draw-head it strikes the coupling-pin and the guide D. It pushes back the pin, which turns on the pivot e far enough to allow it to drop into the link when the cars are coupled. J is a shoulder on the draw-head, which holds the coupling-pin to its place and receives the strain.

Having thus described my invention, what I claim as new, and desire to secure by Letters Patent, is—

The catch F, the coupling-pin C, the guides D and E, and the lifting-rod d, constructed and arranged substantially as described, in combination with the draw-head of a railroad car, for the purpose set forth.

LEWIS O. SCHULTZ.
